(57) **CLAIM**

The ornamental design for a cable crossover attachment, as shown and described.

DESCRIPTION

FIG. 1 is a front perspective view of a cable crossover attachment, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front perspective view showing the cable crossover attachment in use.

The broken lines in FIGS. 1-8 illustrate portions of the cable crossover attachment and form no part of the claimed design. The broken lines in FIG. 9 show environment and form no part of the claimed design.

1 Claim, 6 Drawing Sheets
